A. L. Phelps

Fig. 4

UNITED STATES PATENT OFFICE.

FREDERIC S. SEAGRAVE, OF COLUMBUS, OHIO.

TRUSSSED LADDER.

SPECIFICATION forming part of Letters Patent No. 607,665, dated July 19, 1898.

Application filed April 28, 1898. Serial No. 679,158. (No model.)

To all whom it may concern:

Be it known that I, FREDERIC S. SEAGRAVE, a citizen of the United States, residing at Columbus, in the county of Franklin and State 5 of Ohio, have invented a certain new and useful Improvement in Trussed Ladders, of which the following is a specification.

My invention relates to the improvement of trussed ladders, and has particular relation 10 to the improvement of that class of ladders shown in my former patents, No. 278,051, of May 22, 1883, and No. 347,648, of August 17, 1886.

The objects of my present invention are to 15 provide a trussed ladder with improved means for clamping the legs and trusses of the ladder-frame together, to so construct and apply said connecting or clamping devices as to obviate any tendency toward the connected 20 parts working loose, and at the same time provide improved means for compensating for shrinkage of the adjoining parts and retaining the struts and legs rigidly connected one with the other, and to provide other improvements 25 in details of construction and arrangement of parts, which will be more fully pointed out hereinafter. These objects I accomplish in the manner illustrated in the accompanying drawings, in which—

30 Figure 1 is a view in perspective of a trussed ladder having my improvements thereon. Fig. 2 is a detail view in elevation of one of the clamping-yokes. Fig. 3 is a detail view in perspective of a portion of one of the arms 35 of said clamping-yoke, and Fig. 4 is a similar view showing a modified form of transverse rib or lug.

Similar numerals refer to similar parts throughout the several views.

40 1 represents the parallel legs of a ladder, which are connected in the usual manner by transverse rounds 2.

3 represents the trussed bars or truss frame-pieces, which are bowed downwardly from 45 and have their ends rigidly connected with the end portions of the legs 1 in the manner hereinafter described.

As indicated in the drawings, the legs and 50 trusses are connected in the usual manner and at desirable intervals by struts 4.

In joining the end portions of the struts and legs I employ metallic clamping-yokes

5, which are of the substantially stirrup or U form indicated in the drawings. As shown more clearly in Fig. 2 of the drawings, the 55 parallel arms or members of the clamping-yoke gradually decrease in thickness toward their outer ends, and the arms thus formed are provided on their inner sides, preferably at oppositely-located points, with inwardly-projecting transverse ribs or lugs 6. A clamping-yoke formed as above described is utilized to produce a rigid connection of the corresponding end portions of a ladder truss and leg by causing the upper side of said truss in 60 its end portion and the lower side of said leg to be embraced by the upper and lower arms of the clamping-yoke, said truss being provided on its outer surface with a transverse recess or groove 7 and said leg being provided with a 65 similar transverse groove or recess 8, which are adapted, as shown in Fig. 1 of the drawings, to receive the ribs or lugs 6 of the clamping-yoke. The corresponding ends of the 70 truss and leg being thus made to fit snugly 75 within the yoke, the substantially parallel arms of said yoke are united through the medium of bolts 9, which pass through the end portions of both the truss and leg.

Heretofore and as set forth in my former 80 patent, No. 347,648, it has been common to connect the truss and leg portions with a wooden dowel-pin; but where this connection has been employed it has been found that when the ladder-framework was subjected to the 85 influence of a dry atmosphere the connected parts displayed a tendency through shrinkage toward working loose and the rigid connection originally imparted to the parts was thus impaired.

90 Through the medium of my improved clamping device it will readily be seen that the engagement of the transverse ribs of the clamp with the recesses in the framework, together with the clamping action of the yoke 95 upon the parts, will form an exceedingly rigid connection of the truss and leg ends, and in case of any tendency of the parts to become loose through shrinkage or otherwise it is obvious that by tightening the bolts 9 said parts 100 may be firmly drawn together, thus adding to both the life and utility of the ladder-frame.

As indicated in Fig. 4 of the drawings, I

may produce the ribs 6 in an angular or square form instead of the rounded form shown in the remaining figures.

From the construction and application of 5 the yoke herein described it will readily be seen that an exceedingly strong, durable, and neat form of trussed ladder may be produced and that the means employed for connecting the trusses and legs are such as to admit of 10 the same being produced and applied at a reasonable cost.

Having now fully described my invention, what I claim, and desire to secure by Letters Patent, is—

15 In a trussed ladder, the combination with the legs, rounds and trusses, said legs and

trusses having their adjoining end portions provided with recesses 7 and 8, of metallic clamping - yokes adapted to embrace the united end portions of said trusses and legs, 20 the arms of said yokes being provided with transverse projecting ribs or lugs adapted to engage respectively the transverse recesses of said legs and trusses and bolts adjustably connecting the arms of said yokes and passing through said trusses and legs, substantially as and for the purpose specified. 25

FREDERIC S. SEAGRAVE.

In presence of—

A. L. PHELPS,
EDWARD M. TAYLOR.
